Primary Examiner — Alison M Ofstun(74) *Attorney, Agent, or Firm* — INNOVATION CAPITAL LAW GROUP, LLP; Vic Lin(57) **CLAIM**

The ornamental design for a comb for a hair straightener, as shown and described.

DESCRIPTION

FIG. 1 is a front perspective view of a comb for a hair straightener, showing my new design, shown in an environment of use;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The stipple shading represents a contrast in appearance. The broken lines showing a hair straightener illustrate environmental subject matter and forms no part of the claimed design. The dot-dash broken line illustrate a boundary to the claim and form no part thereof. The remaining broken lines illustrate portions of the comb for a hair straightener and form no part of the claimed design.
